UNITED STATES PATENT OFFICE.

SIDNEY P. JONES, OF WACO, TEXAS, ASSIGNOR TO THE JONES ELECTRIC CORPORATION, OF WACO, TEXAS.

SHAVING MACHINE.

Application filed November 17, 1923. Serial No. 675,252.

To all whom it may concern:

Be it known that I, SIDNEY P. JONES, a citizen of the United States of America, residing at Waco, in the county of McLennan and State of Texas, have invented certain new and useful Improvements in Shaving Machines, of which the following is a specification.

This invention relates to new and useful improvements in shaving machines.

The invention relates to that type of shaving machine which has a shuttle cutting blade operating between side guards for shaving off the beard from the human face and this invention has for its principal object certain improvements and refinements over the device set forth in my co-pending application filed February 8th, 1923, Ser. No. 617,756.

The object of the invention is to provide side guards related to the cutting edges of the shuttle blade in such a manner as to preclude the possibility of injuring the face, but giving the most effective and desirable shaving results. An important advantage of the invention is that the machine may be moved in reverse directions while shaving or in any other direction, which make for quick and smooth shaving without irritation.

An improved feature resides in the curvature and skirt of the guard which enables the barber to do closer work and to handle the machine more freely, as well as making a better disposition of the lather and cut hairs.

Another improvement resides in an amplified blade supporting surface on the carrier, whereby the blade may be more firmly mounted on the carrier and less bearing support by the head is required, thus reducing wear of the blade.

A further improvement is presented in a more convenient and adequate manner of fastening the shuttle blade on the carrier.

An object of the invention is to provide an intermediate gear train between the drive shaft and the cam shaft, whereby a speed reduction may be had between these two shafts.

A further object is to provide a self-oiling bushing for the drive shaft and the cam shaft which will make for more efficient lubrication.

Another object is to provide the carriage with a marginal flange overhanging the shuttle opening, whereby oil is prevented from leaking out and water is excluded when the device is immersed for cleansing.

A construction designed to carry out the invention will be hereinafter described together with other features of the invention.

The invention will be more readily understood from a reading of the following specification and by reference to the accompanying drawings, in which an example of the invention is shown, and wherein:

Fig. 1 is a side elevation of a shaving machine constructed in accordance with my invention,

Fig. 2 is a front elevation of the same,

Fig. 3 is a vertical sectional view on the line 3—3 of Fig. 2,

Fig. 4 is an enlarged end elevation of the machine,

Fig. 5 is a front elevation of the head with the guard plate swung down to expose the blade,

Fig. 6 is a similar view with the blade and carriage removed,

Fig. 7 is an enlarged longitudinal sectional view of the head,

Fig. 8 is a cross-sectional view on the line 8—8 of Fig. 7,

Fig. 9 is an enlarged longitudinal sectional view of the carrier, and

Fig. 10 is a detail of one of the detachable guards.

In the drawings the numeral 10 indicates a tubular handle having a head 11 at its upper end which is provided with a laterally offset bracket 12 extending longitudinally of the handle and head. The bracket is undercut along its intersection with the head to form longitudinal channels 13 which serve as lather accumulating pockets and provide finger grips on each side of the head and bracket, if it is so desired to hold the device. Guard members composed of transverse teeth 14 curve outwardly and downwardly from a connecting bar 15 and terminate at their lower ends in an edge strip 16. The guards have ears 17 at each end receiving screws 18, whereby they are adjustably fastened to the sides of the bracket.

The face of the bracket has guide ribs 19 between which a guideway is formed for a

- carrier 20. A shuttle slot 21 is formed longitudinally of the face between the ribs and the carrier is mounted to reciprocate therein. The carrier has an outwardly directed 5 marginal flange 22 overhanging the ends of the slot and extending laterally over the face of the bracket to the ribs, as is best shown in Figs. 7 and 8. The carrier has a reduced longitudinal boss 23 extending centrally 10 above the flange. One end of the boss is provided with an inwardly directed slit 24, whereby the boss overhangs the flange. An elongated double edge cutting blade 25 has a central slot of such size as to fit around 15 the boss, when confined in the slit, which is accomplished by engaging the blade over the end of the boss and sliding it into the slit and then pressing the other end of the slot portion down around the boss.
- 20 A fastening button 26 having under-cut edges is countersunk in the top of the boss at the end opposite the slit 24. This button has a shank 27 depending through a shoudered slot 30 in the carrier and receiving a 25 coiled spring 28 confined by a nut 29, whereby the button is resiliently held in place. When the blade has been placed the button is turned transversely of the boss, whereby its under-cut edges ride up over the blade 30 and fasten the latter in place. Of course any other suitable means for fastening the blade to the carrier may be used. For cushioning the carrier at the ends of its stroke I provide plungers 31 secured in the 35 ends of coiled springs 33 mounted in recesses 32 at the ends of the slot 21. The plungers have rounded ends engaging in notches or seats 34 in the ends of the carrier.
- 40 The under side of the carrier is concaved to fit on a cylindrical carriage 35 adapted to shuttle in a cylindrical bore 36 formed in the bracket between the channels 13 and contiguous to the slot 21. A screw 37 passing through the carrier engages threads in the carriage; while a screw post 38 having its head countersunk in the boss 23 extends through the carrier and is threaded through the carriage. The inner end of the post 45 is reduced to receive a flanged roller 39 as is best shown in Figs. 7 and 8. The flange of the roller lies in a shuttle slot 40 connecting the bore 36 with a longitudinal cylindrical chamber 41 in the head parallel to the bore.
- 50 One end of the chamber is closed by a cap 42 having a bearing sump 43 for receiving the end of a cam shaft 44. A sleeve 45 is fastened on the shaft and has a grooved cam wheel 46 formed thereon which receives the roller 39, whereby a shuttle motion is imparted to the carriage when the wheel is revolved. The cam shaft is supported by a space collar 47 in a self-oiling bushing 48 55 having circumferential pockets for receiving cup grease. A central circumferential groove 49 receives a set screw 50 in the head, whereby the bushing is held against endwise displacement and rotation. When the bushing is heated by the rotation of the cam shaft the grease will flow through ports 51 and lubricate the shaft. It will be seen that while the grease may overflow into the chamber 41, or the lubricant stored in said chamber and the bore 36, may flow into 60 the slot 21, the flange 22 on the carrier will prevent any leak around the blade 25.
- 65 The pitch of the cam wheel 46 controls the amplitude of the reciprocation of the carriage and experience has shown that a very short movement is required, satisfactory results having been obtained with a shuttle of less than one-eighth of an inch. In order to protect the skin an elongated guard plate 52 has a hinge lug 53 pivoted 65 in the lower end of the bracket. The plate has a stud 55 at its upper end engaging in the aperture of a latch spring 56 secured on the upper end of the bracket. The lug and latch spring hold the guard plate over 70 the blade 25 without creating a frictional contact therewith. The plate has a longitudinal recess 54 in its under side accommodating the boss 23 of the carrier. By springing the latch spring 56 the guard 75 plate 52 may be quickly swung down (as in Fig. 5) to expose the blade.
- 80 The plate is of such width as to expose the cutting edges of the blade which project beyond the edges of the plate. The outer 85 surface of the plate is curved transversely, so that when the plate is pressed against the skin it may be rocked to either side to bring one of the cutting edges into contact with the beard. The plate provides a smooth 90 guide or shoe for running the machine over the face. The arrangement and shape of the guards makes for efficient shaving, but is of course subject to variation. The edges 95 of the blades are substantially flush with the highest points of the guards and the teeth or ribs 14 of the guards may be slightly notched to clear the edges of the blade if necessary. The screws 18 and the ears 17 provide for an adjustment of the guards 100 with relation to the edges of the blade, but it is within the scope of the invention to make the guards stationary. The connecting bar 15 is spaced from the sides of the bracket and this provides elongated openings 105 110 under the blade and which establish connection with the latch channels 13. The parts are exaggerated in the drawings, particularly the curves of the guard plate 52 and the guards, but it is intended that the cutting edges shall only be exposed and presented to such a degree as to cut the beard and not cut the skin of the face. It 115 will be seen that the lather and cut hairs will pass freely through the guards and 120 125 130

openings 57 to the channels 13 or accumulate under the guards.

While various means may be employed for shuttling the blade 25 I have found the 5 cam wheel 46 and component parts to be efficient. The cam shaft may be driven by various means, but where a reduction in speed from the driving means is desired, a gear train is used. An elongated case or 10 housing 58 has an externally screw threaded collar 59 which is screwed into the lower end of the head 11. At the other end of the housing a depending internally screw threaded collar 60 is provided at the 15 other end of the housing and receives the upper end of the handle. A spur gear 61 is mounted on the lower end of the cam shaft 44 in the housing and collar 59. A drive shaft 62 is 20 mounted in the handle and has a pinion 63 on its upper end within the housing and meshing with the gear. A flange 64 extends from the housing at the base of the head and provides an additional surface for gripping 25 the head.

In the handle are mounted a pair of bushings 65 held by set screws 66 and of substantially the same construction as the bushing 48. The bushings support the drive shaft 63 which has its lower end shaped to connect with a flexible drive shaft 67. A universal coupling is formed at the lower end of the handle and includes a plurality of balls 68 pressed through apertures of 35 smaller diameter and retained therein by a circular coiled spring 69. The spring is confined in an annular case 70 on the handle and forces the balls into a groove 67' in the shank of the flexible shaft 67. This coupling will attach various sizes of flexible shafts.

In using the machine the beard is lathered in the usual manner and the machine is attached to the flexible shaft 67, the latter being driven by an electric motor or other power means. It is within the scope of the invention to mount an electric motor (not shown) within the handle 10 for the purpose of revolving the shaft 63. The shaft 50 63 being set in motion causes the blade 25 to shuttle by reason of the reciprocation of the carriage 35 by the cam wheel 46. The speed of revolution of the drive shaft is reduced when transmitted to the shaft 44 by means of the gear 61 and pinion 62, but as before stated the pinion and gear might be omitted and the cam shaft driven directly by the drive shaft. The operator grasps the head 11, the flange 64 and the 55 channels 13 accommodating the fingers and thumb of the operator's hand. The bracket 12 being offset laterally from the handle enables the operator to coil his fingers around the handle under the bracket. The 60 machine is held transversely or at right 65

angles to the position shown in Fig. 2 and with the guard plate 52 in contact with the face of the person being shaved.

It will be noted that the face of the bracket and the blade 25 are substantially parallel to the longitudinal axis of the handle and are offset laterally from said handle, whereby the blade and guards may be placed in contact with the face of the person being shaved and the machine held in a position simulating that in which the ordinary straight edge razor is held. By rocking the head downwardly the lowermost guard teeth 14 and the lower cutting edge of the blade are brought into contact with the beard. The shaving is carried out by a downward sweep of the machine. By again rocking the head, but in the opposite direction, the uppermost guard teeth and cutting edge are brought into contact with the beard, and a reverse stroke may thus be made upwardly of the face. Various strokes may thus be executed and the shaving operation carried out in an expeditious, satisfactory and pleasing manner.

As the shaving proceeds the reciprocation of the blade will be so rapid and of such short length that its movement will not be felt upon the skin. The head being moved in a straight line, the rapidly moving blade will cut diagonally, thus carrying out its work without pulling or irritation. As the lather is removed with cut hairs it passes between the teeth 14 and through the openings 57, to the channels 13 and the spaces 100 under the guards, which are ample enough to accommodate a full shave. The openings 57 make for a rapid clearing of the edges of the blade from the lather. When the shave is finished the machine may be subjected to a stream of hot water for cleansing.

What I claim is:

1. In a shaving machine, a support having a slot in its face, a blade carrier extending through the slot of the support from within the latter, operating means for shuttling the carrier mounted in the support, and a marginal flange on the carrier overhanging the face of the support contiguous to the slot and in close proximity to said face, whereby lubricants are prevented from passing through the slot and outwardly around the carrier, and a shuttle blade mounted on the carrier.

2. In a shaving machine, a handle member, a head carried by the handle, a bracket having its face offset radially from the head and handle, a cutting blade having its edges overhanging the sides of the bracket, guards mounted on each side of the bracket and adjustable toward and from the blade, and means in the head and bracket for imparting a shuttle movement to the blade.

3. In a shaving machine, a handle member a head carried by the handle, a bracket

having its face offset laterally from the head and handle, guide ribs on each side of the face forming a guideway therebetween, a blade carrying element having an overhanging flange in the guideway, a cutting blade mounted on the element and extending over the ribs, and means for reciprocating the carrying element.

4. In a shaving machine, a handle member, a head mounted on the handle, a bracket carried by the head, said bracket having an elongated slot, a carriage mounted to shuttle in the bracket, a carrier mounted on the carriage and reciprocating in the slot of the bracket, means at each end of the slot for cushioning the carrier, a blade mounted on the carrier, and means for reciprocating the carriage.

5. In a shaving machine, a handle member, a head carried by the handle, a bracket having its face offset radially from the head and handle, guards on each side of the bracket, openings between the guards and the sides of the bracket, a cutting blade having its edges contiguous to the guards, a transversely curved guard plate removably mounted over the blade and between the guards, and means in the head and bracket for imparting a shuttle movement to the blade.

6. In a shaving machine, a handle member, a head carried by the handle, a bracket having its face offset radially from the head and handle, guards on each side of the bracket, openings between the guards and the sides of the bracket, a cutting blade having its edges contiguous to the guards, a transversely curved guard plate over the blade, a carriage carrying the blade and mounted in the bracket, and means in the head for imparting a shuttle movement to the carriage.

7. In a shaving machine, a handle member, a head carried by the handle, a bracket having its face offset laterally from the head and handle, guide ribs on each side of the face forming a guideway therebetween, a blade carrying element having an overhanging flange in the guideway, a cutting blade mounted on the element and extending over the ribs, a guard plate mounted over the blade and the carrying element, guards on each side of the ribs, and means for reciprocating the carrying element.

8. In a shaving machine, a handle member, a head carried by the handle, a bracket having its face off-set laterally from the head and handle, guide ribs on each side of the face forming a guideway therebetween, a blade carrying element having an overhanging flange in the guide-way, a cutting blade mounted on the element and extending over the ribs, a guard plate mounted over the blade and the carrying element, guards on each side of the ribs, a recipro-

cating carriage in the bracket connected with the carrying element, a cam wheel in the head reciprocating the carriage, and means in the handle for rotating the cam wheel.

9. In a shaving machine, a head, a bracket extending radially from the head and having its face disposed longitudinally of the head, a cutting blade supported to shuttle over the face of the bracket, and open guard members secured to each side of the bracket inwardly of the blade and overhanging the sides of the bracket.

10. In a shaving machine, a head, a bracket extending radially from the head and having its face disposed longitudinally of the head, a cutting blade supported to shuttle over the face of the bracket, and open guard members adjustable on the sides of the bracket in planes at an angle to the cutting edges of the blade.

11. In a shaving machine, a handle, a head mounted on the handle and having a chamber, a cam wheel mounted in the chamber, a bracket offset laterally from the head, a bore in the bracket, a carriage in the bore, a slot between the chamber and bore, a carriage reciprocating element extending through the slot and engaging the wheel, the bracket having a slot in its face, a carrier mounted in the slot, and carried by the carriage, a flange on the carrier overhanging the face of the bracket, a boss on the carrier, and a removable cutting blade on the flange surrounding the boss.

12. In a shaving machine, a head, a bracket extending radially from the head and having its face disposed longitudinally of the head, a cutting blade supported to shuttle over the face of the bracket, and guard members mounted on the sides of the bracket contiguous to the edges of the shuttle blade and curved inwardly with relation to the sides of the bracket, there being openings between the guard members and the sides of the bracket for the passage of lather inwardly of the bracket.

13. In a shaving machine, an elongated handle, a head supported longitudinally of the handle, a bracket extending radially from the head and having its face disposed longitudinally of the head, the face of the bracket having a longitudinal guide channel, a carrier mounted to reciprocate in the bracket and having a marginal extension overlying the bottom of the guide channel thereof, a shuttle blade mounted on the carrier and extending over the channel of the bracket, means in the head for imparting a shuttle motion to the carrier, a guard member overlying the blade longitudinally between its edges, and guard members attached to the sides of the bracket and having outwardly directed teeth providing openings for the passage of lather to the sides of the bracket.

14. In a shaving machine, the combination with a head having a radially extending bracket, a shuttle blade extending over the face of the bracket in longitudinal relation to the head, and means in the head for shuttling the blade, of guard members attached to the bracket contiguous to the edges of the blade and comprising teeth curved outwardly with relation to the blade and curved inwardly with relation to the sides of the bracket, each member having the outer ends of its teeth connected to an edge strip extending longitudinally of the member.

In testimony whereof I affix my signature.

SIDNEY P. JONES.
